CARTRIDGE CYLINDER FOR A TOY GUN

William A. Hosbach, Jr., Pittsburgh, Pa.

Application June 13, 1958, Serial No. 741,823

4 Claims. (Cl. 124—14)

This invention relates to toy guns which shoot harmless projectiles or bullets, and more particularly to a cartridge cylinder for the toy guns.

My invention provides a cartridge cylinder for the toy gun which ejects a bullet when its hammer is operated by the trigger mechanism of the gun. Specifically, a toy gun equipped with my invention requires a blow from the hammer which is controlled by the trigger mechanism to fire a projectile. Accordingly the hammer and trigger mechanism of the toy gun perform a comparable function to that of the hammer and trigger of a regular gun which fires a powder propelled projectile or bullet.

My invention relates to a toy gun having a frame which mounts a barrel with an inner and outer end, a trigger mechanism and a hammer arranged to be operated by the trigger mechanism and comprises a cylinder mounted for rotation on the frame. Disposed between the inner end of the barrel and the hammer is the cylinder which has at least one chamber radially spaced from its axis of rotation and disposed substantially parallel to the axis of rotation. The chamber has a front open end and a rear open end and is so located on the cylinder that the front end is positioned substantially opposite the inner end of the gun barrel when the cylinder is rotated to a given position. The front end of the chamber is adapted to receive and to hold a projectile and the chamber itself carries a piston disposed therein for movement substantially parallel to the axis of rotation of the cylinder. The piston has a rod with one end connected thereto and with the other end having a means such as a shoulder for engaging and holding the piston in engagement with the rear end of the chamber, thus effecting a cocking of the piston. The cylinder is so positioned relative to the hammer that the rear end of the chamber is substantially opposite the hammer when the front end of the chamber is substantially opposite the inner end of the barrel so that operation of the hammer by the trigger mechanism releases the piston from its engagement with the rear end of the chamber and thereby ejects the projectile from the chamber. Disposed between the piston and the rear end of the chamber is a spring adapted for urging the piston towards the front end of the chamber.

In the accompanying drawings I have shown a preferred embodiment of my invention in which:

Figure 1 is a side elevation view partially in section of a toy gun having my invention;

Figure 2 is an enlarged section view of the cartridge cylinder of the gun of Figure 1; and

Figure 3 is a plan view of a locking plate and resilient ring secured to the cylinder of Figure 2.

The toy gun of Figure 1 comprises a frame 1 and a handle 2 secured thereto. The frame carries a gun barrel 3 having an outer end 4 and an inner end 5, a trigger mechanism 6, and a hammer 7 released by the trigger mechanism. Supported upon the frame 1 is a cylinder pin 8 which mounts a cartridge cylinder 9 for rotation thereon. The cylinder pin 8 extends through a central

2

bore 10 of the cartridge cylinder with the cylinder rotating thereabout.

As shown in Figures 1 and 2, the cartridge cylinder has a plurality of chambers 11 radially spaced from the central bore 10 and disposed parallel thereto. Each chamber has a front open end 12 and a rear open end 13. The chambers are so located in the cartridge cylinder that the front end of each is brought into a position opposite the inner end of the barrel as the cylinder is rotated on the pin 8. At the front end 12 of each chamber is a receptacle 14 which receives and supports a harmless projectile or bullet such as a cork bullet 15. When inserted into the receptacle, the cork bullet fits firmly against the walls thereof so that compressed air assists in ejecting the bullet from the chamber and out through the barrel as described hereinafter.

Disposed in each chamber is a piston or plunger 16 made from a leather ring 17 sandwiched between two steel rings 18 and 19. Secured to the piston 16 and extending rearwardly therefrom is a rod 20 having at its rear end 21 a shoulder 22 located behind a head 23. The piston's travel in the chamber 11 is a reciprocating motion with the leather ring in engagement with the chamber walls so that air under pressure is generated within the chamber between the piston and the cork bullet upon travel of the piston towards the front end of the chamber.

At the rear end of the cylinder 9 is a locking plate 24 having a plurality of holes 25 therethrough with the number of holes coinciding with the number of chambers and with the holes arranged on the plate so that their spacing corresponds to the spacing of the chambers on the cartridge cylinder 9. The locking plate is attached to the cylinder by fasteners 26 and 27 and consequently rotates with the cylinder and it is so attached to the cylinder that each of its holes is opposite the rear open end of a chamber of the cylinder. Since each hole is smaller than the rear open end of the chamber, the plate partially closes the rear end of each chamber.

In each chamber is a compression spring 28 positioned between the piston 16 and the locking plate 24 as shown in Figure 2 chambers 11a and 11b. One end of the spring is in engagement with the locking plate, and the other end is in engagement with the piston 16. Accordingly, the spring urges the piston towards the front end of the chamber as shown in Figure 2, chamber 11a, where the spring is in its fully extended position with projection 29 of the piston extending into the receptacle 14. Chamber 11b, Figure 2, shows the spring in its compression position.

To fire the cork bullet from the receptacle 14, the piston must be cocked and then disengaged from its cocked position by impact from the hammer 7 upon the head 23 of the piston rod. In chamber 11b, Figure 2, the piston is in its cocked position, and in chamber 11a in its fired position. To cock a piston I force the piston into the position shown in chamber 11b by moving it rearwardly against the force of the spring 28 so that the rod head 23 travels out through the rear open end of the chamber and through a hole 25 of the locking plate where a ring 30 engages and forces the head downwardly viewing Figures 1 and 2. Accordingly, the shoulder 22 fits against and engages the locking plate at the periphery of the hole 25. In this way the piston is placed in its cocked position.

The ring 30 is made from rubber, a spring metal, or any other suitable resilient material whereby upon movement of the rod head 23 through the hole 25 of the cocking plate the ring engages the head and forces it downwardly so that the shoulder 22 engages the periphery of the hole 25. The ring 30, once the piston has been cocked, maintains the rod 20 and its shoulder 22 in engagement with the locking plate at the periphery

of the hole until the rod is released therefrom by a blow from the hammer 7. Fastener 26 also secures the ring to the cylinder 9 as shown in Figure 2.

Referring to Figure 1, the gun has a pivoted cocking mechanism 31 which comprises a lever arm 32, a plunger rod 33 and a pivoted elbow 34. One end of the lever arm is secured to the elbow 34 as is one end of the plunger rod. The other end of the lever arm is held in the position shown in Figure 1 just beneath the barrel 3 by a clamp 35 when the cocking mechanism is not in use. The other end of the plunger rod is disposed in a guide way 36 located on the frame 1 when the cocking mechanism is not in use. This guide way, as shown in Figure 1, is so disposed in the frame that it is opposite the forward end of a chamber when the cylinder is rotated so that a chamber is positioned opposite the way. Cocking of the piston 16 results from swinging the lever arm 32 downwardly in a counterclockwise direction viewing Figure 1 whereupon the plunger rod moves to the right, enters the chamber 11 and forces the piston rearwardly until its shoulder 22 is directed into engagement with the locking plate 24 at the periphery of the hole 25 as previously described. Of course the piston 16 may also be cocked by merely inserting a rod (not shown) into the chamber through the receptacle 14 and moving the piston into its cocked position. Once a cylinder is cocked a cork bullet is then inserted into the receptacle 14.

Secured to the cylinder 9 by the fastener 26 is a ratchet wheel 37 having a plurality of notches 38 spaced thereon with the notches so disposed that as the hammer 7 is pulled back, a pawl 40 and ratchet member 41, Figure 1, operated by the hammer 7 advance a chamber with its piston cocked into firing position wherein the front end of the chamber is opposite the inner end of the barrel. Since the hammer 7 is secured to a pivot 45 as is the ratchet member 41, pulling back of the hammer 7 to effect rotation of the ratchet member simultaneously causes the pawl 40, which extends between the ratchet member 41 and the ratchet wheel 37, to rotate the cylinder 9 and bring a chamber with a cocked piston into firing position. The lower end of the pawl 40 is seated in a cavity 46 of the ratchet member and its upper end is in engagement with a notch of the ratchet wheel. Thus, the cork bullet is in position for ejection out through the gun barrel and the rear end of the chamber is in position for the hammer to strike the rod head 23 and fire the cork bullet from the gun.

Ejection of the bullet from its receptacle results from compressed air generated by rapid forward travel of the piston in the chamber and/or by the impact of the projection 29 of the piston against the back end of the cork bullet. Both rapid travel of the piston in the chamber and impact of the projection against the bullet is produced by expansion of the compressed spring upon release of the piston rod from engagement with the locking plate.

The trigger mechanism 6, hammer 7, ratchet wheel 37 and pawl 40 which rotates the cylinder are conventional components of toy guns. Pulling back of the hammer 7 from the position shown in Figure 1 causes the ratchet member 41, a component of the trigger mechanism, to rotate in a clockwise direction so that projection 42 of the trigger 39 engages a notch 43 in the ratchet member. Upon engagement of the projection 42 with the notch 43 the gun is cocked and is fired merely by pulling rearwardly on the trigger 39. When the trigger is pulled rearwardly, the projection of the trigger is removed from its engagement with the notch 43 whereupon a spring 44 and shank 44a immediately cause the hammer 7 to travel rapidly through an arc in counterclockwise direction and strike the rod head 23, thus firing the gun.

The ratchet member has a second notch 47 whereby the hammer may be pulled back a distance short of that required to cock the trigger so that the cartridge cylinder

is freed for rotation to permit cocking of pistons and loading of cork bullets.

A spring 48 maintains the trigger 39 and its projection 42 in engagement with either notch 43 or notch 47 so that the gun is ready for firing upon cocking of the hammer 7.

Disposed around the periphery of the cartridge cylinder is a plurality of cylinder locking grooves 49 with each groove being positioned so that it corresponds to the position of a chamber. In the frame 1 is a cavity 50 for a spring 51 and a ball 52 adapted to partially fit into a cylinder locking groove and thereby lock the cylinder in position so that a chamber is held in its firing position and is not free to rotate when the hammer is released for firing the gun.

My invention in a cartridge cylinder for a toy gun imparts reality to firing of the toy gun as compared to firing a conventional gun with powder propelled projectiles or bullets. In other words, a toy gun equipped with my cartridge cylinder requires a blow by the hammer to fire a cork bullet, as some real guns require a blow by the hammer to fire a cartridge.

My invention has a simple and sturdy construction so that a toy gun incorporating the cartridge cylinder will withstand vigorous use by children without being injured or rendered inoperative.

While a certain preferred embodiment of my invention has been shown and described, it will be understood that it may be otherwise embodied within the scope of the appended claims.

I claim:

1. In a toy gun having a frame mounting a barrel with an inner and an outer end, a trigger mechanism and a hammer arranged to be operated by said trigger mechanism, the combination comprising a cylinder mounted for rotation on said frame and disposed between the inner end of the barrel and said hammer, said cylinder having at least one chamber radially spaced from its axis of rotation and disposed substantially parallel to the axis of rotation, said chamber having a front end and a rear end and being so disposed on said cylinder that its front end is located substantially opposite the inner end of said barrel when the cylinder is rotated to a given position, said chamber being adapted to receive a projectile and having a piston disposed therein for movement substantially parallel to the axis of rotation of the cylinder, said piston having a rod with one end connected thereto and with the other end having a means for engaging and holding the rod in engagement with the rear end of the chamber, thereby cocking said piston, said cylinder being so disposed relative to the hammer that the rear end of the chamber is substantially opposite said hammer when the front end of the chamber is substantially opposite the inner end of the barrel, said engaging and holding means of said rod having a part which is positioned at the rear end of its chamber when said engaging and holding means is in engagement with the rear end of the chamber and which is opposite said hammer when the chamber has its front end opposite the inner end of the barrel so that operation of the hammer by the trigger mechanism causes the hammer to engage said part of the engaging and holding means and uncocks said piston and thereby ejects a projectile from the chamber, a spring means disposed between said piston and the rear end of said chamber and being adapted to urge the piston forwardly in said chamber.

2. The combination of claim 1 characterized by resilient means adjacent the rear end of said chamber for urging said means of the rear end of said rod into engagement with the rear end of said chamber.

3. The combination of claim 1 characterized by pivoted means pivotally mounted on said frame for cocking said plunger, said pivoted means having a cocking member connected thereto and positioned to enter said chamber and force said piston rearwardly in said chamber so

that said means on the rear end of the rod engages the rear end of the chamber, thereby cocking said piston, and having a lever rod with one end connected thereto and disposed to move said pivoted means about its mounting upon travel of the other end of the lever through an arc, thereby causing said cocking member to enter said chamber or to withdraw said cocking member therefrom depending upon direction of travel of the other end.

4. The combination of claim 1 characterized by said piston having a head adapted for travel in said chamber in engagement with the inside walls thereof so that for-

ward movement of the piston within the chamber compresses air in the forward part of the chamber for ejection of the projectile.
